UNITED STATES PATENT OFFICE

119,824

DESIGN FOR A TRACTOR

David B. Baker, Riverside, and William C. Rosenthal, Chicago, Ill., and Theodore H. Koeber, Fort Wayne, Ind., assignors to International Harvester Company, a corporation of New Jersey

Application September 22, 1939, Serial No. 87,356

Term of patent 14 years

To all whom it may concern:

Be it known that we, David B. Baker, William C. Rosenthal, and Theodore H. Koeber, citizens of the United States, residing at Riverside, in the county of Cook and State of Illinois, Chicago, in the county of Cook and State of Illinois, and Fort Wayne, in the county of Allen and State of Indiana, respectively, have invented a new, original, and ornamental Design for a Tractor, of which the following is a specification, reference being had to the accompanying drawings, forming part thereof, in which:

Figure 1 is a perspective, three-quarter side view of a tractor showing the new design; and,

Figure 2 is a perspective, three-quarter front view of the tractor shown in Figure 1, also showing the new design.

The dominant features of the design reside in the radiator, the hood and fuel tank and the frame and power plant housing; and their relationship to each other and to the chassis, all as shown.

We claim:

The ornamental design for a tractor, as shown and described.

DAVID B. BAKER.
WILLIAM C. ROSENTHAL.
THEODORE H. KOEGER.
